VARIABLE PITCH PROPELLER BLADE ROOT CONSTRUCTION

Filed March 15, 1946

Fig. 1

INVENTOR

F. Tornes + H. J. Lissau

By Watson, Cole, Grindle + Watson

Applicant's name is registered in the United States Patent Office under the name of Ferdinand Tornes, and the name of the assignee is the same. The present application is a continuation-in-part of application Serial No. 654,752, filed March 15, 1945, now abandoned, and is directed to the same subject matter.

The present invention relates to a hub construction for ship propellers and turbines with turnable blades which can be turned when in operation. It is an object of the invention to provide a hub construction which is simple, strong, and reliable, and which can be easily assembled and disassembled.

UNITED STATES PATENT OFFICE

VARIABLE PITCH PROPELLER BLADE ROOT CONSTRUCTION

Ferdinand Tornes and Nils Johannes Liaaen,
Aalesund, Norway

Application March 15, 1945, Serial No. 654,752
In Norway March 6, 1945

3 Claims. (Cl. 170—160.47)

1

The present invention relates to a hub construction for ship propellers and turbines with turnable blades which can be turned when in operation.

It is known in propellers and turbines with turnable blades to secure the blades by screw bolts in the blade root to a turnable disc (crank disc) inside the hub, by means of which the blade is turned. In a known construction a flange on this disc forms, together with a radial face on the blade root a circular groove in the fastening end of the blade. In this groove a ring is provided which by means of screws in its outer edge is secured to the hub and which takes up the centrifugal force and the bending moment on the blade. In this construction the disc is first inserted radially in the hub, whereafter the ring which partly covers the disc is screwed to the hub and the blade screwed to the disc.

It has also been suggested to secure the blade by means of screw bolts in the root of the blade to an outer disc and an inner crank disc, coming to rest one on each side of a ring made in one piece with the hub, the inner disc being made in several parts of such dimensions that they can be passed centrally through the opening of the ring and thereafter assembled and screwed to the blade root.

According to the present invention the hub and the crank disc are made so that the crank disc can be passed in one piece into the hub, axially through an opening in the end of the same, and that it comes to rest against a bearing face made in one piece with the hub. The construction thus becomes simpler, cheaper and stronger than the known constructions, and the mounting of the blade also becomes simpler.

The drawing illustrates an example of an embodiment of a propeller according to the invention. Fig. 1 is a longitudinal section through hub and blade root and Fig. 2 is partly a transverse section through the same and partly a view of the hub from behind with the aft cover removed.

The propeller shaft 1 is connected to the hub 2 by means of a flange, the hub being provided with a ring 3 for each blade, the ring having two faces 3a and 3b at right angles to the axis of the blade, and a face 3c which is cylindrical about the axis of the blade. The root of propeller blade 4 is formed so that it seats with a running fit against the faces 3a and 3c on the hub 2. A sealing ring 4a is inserted between the blade and the hub. To the blade 4 is secured, by means of the screw bolts 6, a crank disc 5 which is further secured against rotation by means of the pins 7. The

crank disc 5 is provided with a face which rests against the face 3b in the hub 2. On the crank disc 5 is a crank pin 8 integral with the disc. On the pin 8 is the nut 9 which is moved by the connecting-link made in three parts 10, 11, and 12. The connecting-link is secured to the rod 13, abutting against a shoulder 13a on the same and secured by means of the nut 14. The parts 10, 11, and 12 of the connecting-link are further secured together by the screw bolts 15. The rod 13 has bearings 16 and 17 in the hub. The rod 13 is secured to the rod 18, which is movable longitudinally by any conventional means, such as a servomotor. The hub 2 is provided with an opening 19 in its end sufficiently large to allow the crank disc 5 to be passed axially into the hub, and installed in place resting against the face 3b in the same. The opening 19 is closed by means of the cover 20 which is secured by the screw bolts 21.

The propeller blades are fitted in the following way.

The hub is secured to the shaft 1 in which the rod 18 is inserted, and the rod 13 is connected to this rod. The discs 5 are brought in place and the blades 4 secured by means of the screw bolts 6 and the pins 7. When all blades are fitted in this way the blades are swung so that the pins 8 on the discs are in the center line of the blade pointing to the opening 19. The part 10 of the connecting-link thereafter is slid axially in on the rod 13, a groove 10a being provided for the pin 8. The blades 4 then are swung so that the pin 8 is moved somewhat sideways to the rod 13, thereby giving room for sliding the nuts 9 on the pins 8. These nuts are kept in place by the part 11 of the connecting-link when the same is slid on the rod 13, this part having a face 11a against which the nut 9 can rest. The last part 12 of the connecting-link is slid on the rod 13 and the whole connecting-link secured to the rod by means of the screw nut 14. For further securing of the parts together the screw bolts 15 are inserted. Finally, the cover 20 is secured by means of the screw bolts 21.

If the hub is made with sufficiently large diameter the connecting-link may be made as one unit. The connecting-link pre-assembled with nuts and crank discs then may be inserted through an opening of the necessary size in the end of the hub. For propellers with two blades this can be done without increasing of the diameter of the hub.

The manner of operation is the usual. When the rod 13 is moved one way or the other in the

propeller shaft this movement is by means of the connecting-link converted into a turning of the several blades about their respective axes, whereby the pitch of the turbine or propeller may be varied.

We claim:

1. In an adjustable pitch propeller or the like, a hollow hub, a plurality of blades mounted radially therein and means operatively connected to the inner ends of said blades for turning them about their axes, each said blade having adjacent its root end an annular flange and said turning means comprising a crank disc secured to the root of said blade, the said flange and the said crank disc forming between them a circular groove for a bearing ring in the hub, the connection between the blade and the crank disc being established by means of screw bolts extending through the said flange at the root end of the blade and screwed into the said crank disc, said hub having an axial opening of a diameter sufficient to permit passage of said crank discs into the interior of said hub, said flange and said crank disc bearing against the outer and inner surfaces respectively of a bearing ring made integral with the hub in the wall of the same.

2. In an adjustable pitch propeller as defined in claim 1 a blade-turning means comprising a member movable axially of said hub, a crank pin on each of said crank discs, and means operatively connecting said member and said pins, this means comprising a nut on each said crank pin, three parts slidable longitudinally onto said member, two of said parts being spaced apart by said third part and being adapted to accommodate therebetween the said nuts on said crank pins, and means for securing said parts together and for securing the same in place on said member.

3. In an adjustable pitch propeller or the like,

5 a hollow hub, a plurality of blades mounted radially therein, and means operatively connected to the inner ends of said blades for turning said blades about their axes, each said blade having an annular flange adjacent its root end, said hub having a radial opening for each blade, the periphery of each said opening having a flange providing a seat for the flange of said blade root, and said turning means comprising a crank disc secured to said blade root and seating upon the inner surface of said hub flange, said hub having an axial opening of a diameter sufficient to permit passage of said crank discs into the interior of said hub, said blade-turning means comprising a member movable axially of said hub, a crank pin on each of said crank discs, and means operatively connecting said member and said pins, said last means comprising a nut on each said crank pin, three parts 10 slidable longitudinally onto said member, two of said parts being spaced apart by said third part and being adapted to accommodate therebetween the said nuts on said crank pins, and means for securing said parts together and for 15 securing the same in place on said member.
